CLAIM

We claim the ornamental design for a speaker, as shown and described.

DESCRIPTIONFIG. 1 is a top, rear, right perspective view of the claimed design in an open configuration;
FIG. 2 is a top plan view thereof;
FIG. 3 is a bottom plan view thereof;
FIG. 4 is a left side elevation view thereof;
FIG. 5 is a right side elevation view thereof;
FIG. 6 is a front elevation view thereof;
FIG. 7 is a rear elevation view thereof;
FIG. 8 is a top, rear, right perspective view of the claimed design in a closed configuration;
FIG. 9 is a top plan view thereof;
FIG. 10 is a bottom plan view thereof;
FIG. 11 is a left side elevation view thereof;
FIG. 12 is a right side elevation view thereof;
FIG. 13 is a front elevation view thereof; and,
FIG. 14 is a rear elevation view thereof.
The broken lines formed by dashes show unclaimed subject matter and form no part of the claimed design.

The broken lines formed by dashes show unclaimed subject matter and form no part of the claimed design.
